UNITED STATES PATENT OFFICE.

JAMES E. FLITCROFT, OF OCEAN GROVE, NEW JERSEY, ASSIGNOR TO PATRICK WALL,
OF PITTSBURGH, PENNSYLVANIA.

GASOLENE BLOW-TORCH.

1,030,465.

Specification of Letters Patent. Patented June 25, 1912.

Application filed December 26, 1911. Serial No. 667,730.

To all whom it may concern:

Be it known that I, JAMES E. FLITCROFT, a citizen of the United States, residing at Ocean Grove, in the county of Monmouth and State of New Jersey, have invented a new and useful Gasolene Blow-Torch, of which the following is a specification.

The present invention relates to improvements in gasolene blow torches, the primary 10 object of the present invention being the provision of a blow torch having a novel form of gas and air mixing means disposed in operable relation to the gasolene supply valve, the said means terminating in an enlarged cylindrical combustion chamber having 15 a flame reducing grid or baffle, whereby the flame emitted from the combustion chamber will be tapered to a fine point to render the torch especially adapted for brazing and other work which requires the concentration of an intense heat.

A further object of the present invention is the provision of a novel form of air supplying pump having mounted in the lower 20 end thereof a spring closed valve which prevents the entrance of the liquid or gasolene within the reservoir of the lamp from entering the pump but permits the proper introduction of the air to produce the desired 25 pressure to feed the gasolene to the torch, a novel form of locking means being disposed to retain the plunger of the pump in down stroke position, at which time the 30 lower end of the pump is closed by an auxiliary sealing means so that no leakage of the pressure from within the tank or reservoir of the lamp will enter the pump cylinder to cause an outward movement of the 35 plunger.

40 A still further object of the present invention is the novel arrangement and positioning of a handle, said handle being disposed at such an angle with relation to the torch body or tank as to render the manipulation 45 or direction of the flame to the object to be heated more easily, said handle being so disposed as to render the manipulation of the torch more natural and so that the operator is permitted to grip the handle at an angle 50 of substantially 45 degrees to the body or upright position of the torch.

With the foregoing and other objects in

view which will appear as the description proceeds, the invention resides in the combination and arrangement of parts and in 55 the details of construction hereinafter described and claimed, it being understood that changes in the precise embodiment of invention herein disclosed can be made within the scope of what is claimed 60 without departing from the spirit of the invention.

In the drawings—Figure 1 is a vertical longitudinal sectional view through the complete torch, the valve being in closed position, with the pump plunger locked in inmost or down stroke position. Fig. 2 is a section taken on line 2—2 of Fig. 1. Fig. 3 is a section taken on line 3—3 of Fig. 1. Fig. 4 is a section through the upper end of the air pump, at right angles to the section shown in Fig. 1. Fig. 5 is an enlarged detail sectional view of the lower end of the air supplying pump showing the construction of the valves and mountings thereof. Fig. 6 is a perspective view of the spring 70 actuated valve mounted at the extreme lower end of the pump.

Referring to the drawings, the numeral 1 designates the tank or reservoir which is 80 of the usual construction and is provided with the hollow boss or projection 2 having the upper exteriorly threaded end 3, a brace or arm 4 being connected upon the same side of the tank or reservoir 1 as the boss 2, 85 and projecting outwardly in a line parallel with the bottom or lower edge of the tank and carrying removably at its upturned end 4' the gripping handle 5 whose upper end is held by means of the lug 5' formed 90 integral with the exterior of the boss 2, so that the center line of the handle will be at an angle of substantially 45 degrees from a line drawn parallel with one of the walls or a line taken through the center of the 95 tank 1. By this means the operator gripping the handle 5 can manipulate the torch with more ease and without a tiring effect, than where the handle is mounted in a vertical line and parallel to the center line of the 100 tank or reservoir.

Mounted within the tank is the usual liquid hydrocarbon conveying tube 7 secured by the washer 8, while disposed there-

above and in line with the outlet aperture 9 is the torch carrying standard or tube 10. A wick 11 is disposed in both of the tubes 7 and 10. By this means the gasoline within the tank is filtered as it is forced through the wick in the tubes 7 and 10 to the torch body 14, thus preventing the burner from being clogged and at the same time assisting in an even flow of gasoline to the torch body 14, which is connected by means of its tubular boss to the upper end 12 of the standard 10, said standard 10 further carrying the drip cup 13. Mounted in the top of the tank or reservoir is a removable cap 6, whereby the tank may be filled with the gasoline or other fluid hydrocarbon.

The torch body 14 has formed therein the liquid hydrocarbon conveying channels 16 and 17 which terminate in the concentrically disposed tapered outlet 18 controlled by a needle valve 19, the stem of which is mounted through the projecting end 20 and stuffing box 21 and is provided with the operating wheel or handle 22. The fluid hydrocarbon under pressure when supplied to the torch body is admitted from the end of the tapered bore 18 concentrically of the enlarged air and gas mixing chamber 23, which is provided with the series of air inlet elongated slots 24, said chamber being made substantially in the form of two oppositely disposed truncated cones, whereby the air, due to the projection of the flow or stream of fluid hydrocarbon into the education tube or bore 25 of the main body 14, will be drawn through the longitudinally disposed slots 24 and be thoroughly mixed within said chamber and the education tube 25 before the entrance of the carbureted air into the enlarged cylindrical combustion chamber 26 formed at the extreme outer end of the torch body 14. Through the walls of the cylindrical combustion chamber are provided a plurality of equidistantly spaced apertures 27, while mounted removably in the open end of the combustion chamber is a disk 28, which, through the medium of the removable screws 29 is fastened in the outer end of the combustion chamber, as clearly shown in Fig. 2. This disk is provided with the concentrically disposed aperture 30 having radiating therefrom the plurality of radial slots 31, which provide a means for splitting the partly burned gases, said disk 28 being a baffle plate whereby the flame due to the shape of the same and the radiating slots 31 is caused to taper outwardly from the extreme end of the combustion chamber 60 to an exceedingly sharp point, thus producing the desired pointed flame for brazing and other purposes.

In order to supply the proper amount of air and the consequent pressure to the contents of the tank or reservoir 1 to properly

feed the spray of fluid hydrocarbon into the torch body, the removable pump cylinder 32 is disposed within the bore of the boss 2 of the lamp body, the rim 33 of said cylindrical pump body being disposed to receive the washer 33' and with the cap or cover 34 properly seats the said pump within the bore and secures the same air and liquid tight upon the upper extreme end of the hollow boss 2 of the lamp. The removable cap 34 is provided with the concentric aperture 35 through which is slidably mounted for reciprocation the stem 36 carrying the plunger 39 at one end and the operating button or handle 38 at the opposite end, a spring 37 being disposed upon the stem and the boss of the removable cap 34 so as to act as a cushioning means for the plunger upon the up-stroke of the same. Carried upon the lower or extreme inner end of the stem 36 is a concaved disk 40 fixed upon, to seal the upper end of the truncated conical casing 41 which is removably mounted in the concentric aperture in the lower end of the pump cylinder 32 and projects within the body to be engaged or incased by the cupped portion of the concaved disk 40 when the plunger is locked in the position as shown in Fig. 1. Formed concentrically and integrally with the inner end of the valve carrying casing 41 is the reduced tube 42 forming the air outlet for the pump and providing upon its lower end a seat for the valve 47 which is mounted within the removable tube 44, whose upper end is threaded into the open end of the valve casing 41, said tube being provided with the air outlet aperture 45 in its lower end and having mounted therein the spring 46 which normally bears upwardly upon the lower side of the valve 47 to hold the same in valve seating position with the lower end of the tube 42, a leather seat 48 being carried by the valve 47. The said valve 47 is provided with the spring and spaced terminals 49 which ride upon the wall of the tube 42 and thereby properly guide the valve 47 into and out of seating relation and also when forced downwardly, due to the in-stroke of the plunger 39, slides downwardly upon the stem 42 to permit the emission of air through the spaces between the arms into the tube 44 and finally into the tank. By this construction it will be seen that upon the down-stroke of the plunger 39 the air will be forced within the tank or reservoir 1 and that by reason of the spring 46 and the valve 47, that upon the up-stroke the pressure within the tank and the said spring will close the said valve to prevent any leakage of air or the liquid into the pump cylinder 32, thus preventing any action that tends to push the plunger upwardly into extended position or up-stroke, as is the general fault with most blow torches.

In order to lock the plunger in its downward position and thereby place it out of the way in manipulating the blow torch, the oppositely disposed integral lugs 50 are formed 5 upon the boss 2 while pivotally connected thereto is the bail 51, preferably made of wire and provided with the spaced terminals 52 with the eyes 53 upon the ends thereof, said eyes being pivotally mounted upon the 10 respective lugs 50, so that the coils 54 carried by the bridging portion of the bail 51 may be brought into and out of contact as at a with the outer end of the button or handle 38 of the plunger stem, thus retaining the 15 plunger stem in the down or instroke position, and as the said coil 54 permits a yielding tension upon the upper end of the knob or handle 38, the said plunger 39 is held yieldingly downwardly into valve seating 20 position, thus locking the same in an immovable position and permitting the ready manipulation of the torch by means of the handle 5 without any interference from the upper end of the plunger stem.

25 What is claimed is:

1. A blow torch, having a burner provided with an enlarged double cone-shaped fluid and air mixing chamber provided with longitudinally disposed air inlet slots in the 30 walls thereof, a valve controlled fluid nozzle projecting concentrically of and within said chamber, an induction tube of lesser diameter than the mixing chamber leading from said mixing chamber, an enlarged cylindrical combustion chamber at the opposite end of 35 the induction tube, and a flame directing disk removably mounted in the outer end of the combustion chamber.

2. A blow torch, having a burner provided with a fluid and air mixing chamber having an enlarged intermediate portion and reduced end and provided with longitudinally disposed air inlet slots in the walls thereof, a valve controlled fluid nozzle concentrically of and projecting into said chamber, an induction tube leading from said chamber, an enlarged cylindrical combustion chamber at the opposite end of the tube and a removable flame forming baffle disk 50 disposed in the extreme outer end of the combustion chamber, said disk having a concentric aperture and radiating slots, said aperture being of substantially the same diameter as the induction tube.

55 3. A blow torch, having a burner provided with a fluid and air mixing chamber having an intermediate enlarged portion and oppositely disposed reduced ends and provided with longitudinally disposed air inlet slots in the walls thereof, a valve controlled fluid nozzle concentrically of said chamber, an induction tube leading from said chamber, an enlarged cylindrical combustion chamber at the opposite end of the 60 tube, and a flame forming baffle disk re-

movably disposed in the extreme outer end of the combustion chamber, said baffle disk being provided with a concentric flame emitting aperture having a plurality of radially disposed slots leading therefrom.

70

4. A blow torch, having a fluid reservoir provided with an angularly disposed hollow boss, and an air supplying means removably insertible within the bore of the boss and comprising a pump cylinder, a plunger reciprocatingly mounted therein, a stem connected to the plunger and projecting exteriorly of the body, a removable cap surrounding the stem for locking the pump body within the boss, and a bail pivotally connected to said boss and disposed to engage the outer end of the stem to lock the same in in-stroke position.

75

5. A blow torch, having a fluid reservoir provided with an angularly disposed hollow boss, and an air supply means removably insertible within the bore of the boss and comprising a pump cylinder, a plunger reciprocatingly mounted therein, a stem connected to the plunger and projecting exteriorly of the body, a removable cap surrounding the stem for locking the pump body within the boss, a bail pivotally connected to said boss and disposed to engage the outer end of the stem to lock the same in in-stroke position, 90 and a spring coil carried by said bail and disposed to yieldingly engage the outer face of the stem to yieldingly hold the stem in in-stroke position.

85

6. A blow torch, having a fluid reservoir, 100 a pump, a boss carrying said pump and formed integral and at one side of the reservoir, an arm connected to the same side of the reservoir near the bottom thereof and projecting at right angles to the center line 105 of the reservoir, said arm being provided with an upturned extremity, a lug formed integral with the boss of the reservoir, and a cylindrical handle connected to the upturned end of the arm and to said lug of 110 the boss.

7. A blow torch, having a fluid reservoir, 115 a pump, a boss carrying said pump and formed integral and at one side of the reservoir, an arm connected to the same side of the reservoir near the bottom thereof and projecting at right angles to the center line of the reservoir, said arm being provided with an upturned extremity, a lug formed 120 integral with the boss of the reservoir, and a cylindrical handle connected to the upturned end of the arm and to said lug of the boss, said handle being disposed at an angle of 45 degrees to the center line of the reservoir.

125

8. A blow torch, having a fluid reservoir, 130 a pump, a boss carrying said pump and formed integral and at one side of the reservoir, an arm connected to the same side of the reservoir near the bottom thereof and

135

projecting at right angles to the center line of the reservoir, said arm being provided with an upturned extremity, a lug formed integral with the boss of the reservoir, and a 5 cylindrical handle connected to the upturned end of the arm and to said lug of the boss.

In testimony that I claim the foregoing

as my own, I have hereto affixed my signature in the presence of two witnesses.

JAMES E. FLITCROFT.
